UNITED STATES PATENT OFFICE.

JAMES B. LADD, OF ARDMORE, PENNSYLVANIA, ASSIGNOR TO UNITED STATES CAST IRON PIPE AND FOUNDRY COMPANY, OF BURLINGTON, NEW JERSEY, A CORPORATION OF NEW JERSEY.

METHOD OF AND APPARATUS FOR CHARGING ROTATING PIPE-MOLDS.

1,351,767.

Specification of Letters Patent. Patented Sept. 7, 1920.

Application filed November 1, 1918. Serial No. 260,658.

To all whom it may concern:

Be it known that I, JAMES B. LADD, a citizen of the United States of America, and a resident of Ardmore, in the county of 5 Montgomery, in the State of Pennsylvania, have invented certain new and useful Improvements in Methods of and Apparatus for Charging Rotating Pipe-Molds, of which the following is a true and exact description, reference being had to the accompanying drawing, which forms a part thereof.

The general object of the present invention is to provide an improved method of, 15 and apparatus for supplying molten casting metal to elongated horizontal rotating molds of centrifugal casting machines, and particularly to centrifugal casting machines for forming relatively large size cast iron pipe. 20 Heretofore it has been the practice to charge molds of centrifugal pipe casting machines with molten metal by feeding the metal simultaneously and with substantial uniformity all along the length of the mold, 25 the typical mold charging device heretofore used being a trough, axially disposed in the mold and rotated to empty into the mold the charge of molten metal contained in the trough through a discharge orifice, or over 30 a discharge lip, running substantially the length of the mold.

The construction and manipulation of such a rotatable trough mold charging device is not a simple matter, and difficulty is 35 experienced in keeping the trough in operative condition, and particularly in preventing substantial and disturbing accumulations of solidified charge forming metal on the surfaces of the trough. In proceeding 40 in accordance with the present invention, the mold is not charged with molten metal simultaneously along the length of the mold, but progressively from one end of the mold to the other. To accomplish this progressive 45 charging of the mold it is necessary, of course, to complete the charging of the mold in a very short period of time, in order to insure a casting of uniform thickness and of homogeneous character. The length of the 50 period in which the charging operation must be completed depends, of course, upon the length and weight of the casting formed and also upon the character of the mold. In

forming an ordinary cast iron pipe in a mold in which the wall of the mold cavity 55 is formed of metal, the charging period will ordinarily be a matter of a second or two. In forming a similar casting in a sand lined mold, the duration of the charging operation may be substantially greater, but with such 60 a mold the charging period will ordinarily be a matter of comparatively few seconds.

In practice my invention, considered in its broader aspects, comprises two general modes of operation. In one of these modes 65 the molten metal is discharged into one end of the rotating mold in the form of an axial jet, and the velocity of the jet stream is progressively varied as required to progressively distribute the molten metal along 70 the length of the mold. In the second mode of practising my invention the mold is charged through a conduit discharging at one end, which projects into the mold and is moved axially therein to distribute the 75 stream of molten metal flowing through it at a relatively low velocity, along the length of the mold. This mode of charging the mold is particularly adapted for use in charging pipe molds only when the latter 80 are sand lined, but the first described method may be used either with metal or sand lined molds. I have devised, and my invention consists in part, in various mechanisms for 85 charging molds in each of the two modes referred to above.

The various features of novelty which characterize my invention are pointed out with particularity in the claims annexed hereto and forming a part of this specification. 90 For a better understanding of the invention, however, and the advantages possessed by it reference should be had to the accompanying drawings and descriptive matter in which I have illustrated and described preferred forms of mechanism and 95 preferred methods used in practising my invention.

Of the drawings:

Figure 1 is a diagrammatic elevation of 100 mold casting apparatus comprising means for charging a mold by a jet of molten metal of varying velocity.

Fig. 2 is a sectional elevation of a portion of the apparatus shown in Fig. 1. 105

Fig. 3 is a view taken similarly to Fig. 2,

illustrating a modification of the apparatus shown in Figs. 1 and 2.

Fig. 4 is an end view of a portion of the apparatus shown in Fig. 1.

5 Fig. 5 is a sectional elevation on a larger scale than Fig. 1 of a portion of the apparatus shown in the latter figure.

10 Fig. 6 is a sectional elevation of a second type of apparatus for charging the mold by means of a jet of varying velocity.

Fig. 7 is a sectional elevation illustrating a modified form of the type of apparatus shown in Fig. 6.

15 Fig. 8 is an end elevation, partly in section, illustrating still another type of apparatus for charging a mold by a jet of varying velocity.

Fig. 9 is a plan, in section on the line 9—9 of Fig. 8.

20 Fig. 10 is a sectional elevation, diagrammatic in character, illustrating apparatus for charging the mold through a conduit extending into, and axially movable in the mold.

25 Fig. 11 is a section illustrating a modification of a portion of the apparatus shown in Fig. 10.

Fig. 12 illustrates a modification of the type of apparatus shown in Fig. 10, and

30 Fig. 13 represents a second modification of the type of apparatus shown in Fig. 10.

The apparatus shown in Figs. 1, 2, 4 and 5 comprises a rotating metal mold A, which may be supported and rotated by any usual 35 or suitable means, not illustrated herein, as they form no part of my present invention. B represents a molten metal reservoir or charging ladle, which is shown as formed with a discharge passage B' open to the interior of the receptacle B at the bottom of the latter, and terminating at its outlet end in a horizontal portion, from which the molten metal passes into a nozzle C detachably secured to the receptacle B and axially 40 disposed with respect to the mold A. The mold A, shown in Figs. 1 and 2, is a metal mold and by the term "metal mold," as used herein, I mean a mold having the wall of the mold cavity formed wholly or largely 45 of metal. The nozzle C has its discharge end barely inserted in the mold A, as shown in Figs. 1 and 2. When the mold has a sand lining A³ as does the mold AA, shown in Fig. 3, the nozzle C may be replaced by a 50 nozzle CC, having its bore substantially larger than the bore of the nozzle C, because of the lower jet velocity permissible with a non-metallic mold. The nozzle CC advantageously projects into the mold an appreciable distance, as shown in Fig. 3, during a 55 portion of the mold charging operation.

The receptacle B is provided with an inlet B² at its upper end for compressed air for expelling the molten metal from the receptacle through the discharge passage B'

and nozzle C or CC at the desired velocity. As shown, the receptacle B is formed with a filling opening, sealed during the mold charging operation by a movable cover B³. The receptacle B is provided with trunnions 70 B⁴ for mounting the receptacle on a suitable support so as to permit the receptacle to be tilted in filling and emptying the same, though it is to be understood that in charging a mold in accordance with the present 75 invention, the receptacle B will ordinarily not be tilted during the mold charging operation.

As shown in Figs. 1 and 4 the support in which the trunnions B⁴ are journaled is a 80 frame or bracket D² carried by the platform of a weighing scale D, which, as shown, is mounted on wheels D', running along stationary track rails E. The scale D

is connected to the plunger of a fluid pressure motor cylinder F by means of which the scale may be moved to carry the receptacle B into and out of the mold charging position preparatory to, and at the end of a mold charging apparatus; and, in the case 90 of the sand lined mold arrangement of Fig. 3 may be moved to carry the nozzle CC out of the mold cavity during the final portion of the charging operation. The platform scale comprises two beams D⁵ and D⁶, both 95 of which are elevated by the weight on the scale platform at the beginning of the mold charging operation, but are depressed on the decrease in weight of molten metal in the receptacle B occurring as the mold 100 charging operation proceeds. The scale mechanism is so arranged that the beam D⁵ will be depressed in an early stage of the mold charging operation, while the lever D⁶ will not be depressed until the mold 105 charging operation is practically completed.

The depression of the lever D⁶ is relied upon to automatically vary the jet velocity with which the molten metal is forced out of the receptacle B and discharged into the mold, 110 and the depression of beam D⁶ stops the discharge of molten metal. As shown in Fig. 1, on the depression of the beam D⁵, which, as already stated, occurs during an early stage in the mold charging operation, the 115 beam engages an electrical control G. This closes an electric current, including contact G, scale beam D⁵, electric supply conductors 1 and 2, and the magnetizing winding of an electromagnet H. The energization of 120 the electromagnet H causes the armature H' of the latter to move to the right, as shown in Fig. 1. The armature H' is connected by a link to the operating lever I' of a throttle valve I in a compressed air supply pipe I¹⁰. To insure a prolonged closing movement of the throttling valve I at the proper rate when the electromagnet H is energized, I connect the armature H' to a piston H² working in a retarding cylinder 125 130

H³. The latter has its opposite ends connected by a by-pass H⁴ in which is located a regulating valve H⁵. The scale beam D⁶, when depressed, engages a contact GA and thereby closes an electric circuit, including conductors 3 and 4, a contact GA engaged by the scale beam D⁶, and the winding of an electromagnet HA. The armature of the latter is connected by a link to the operating 10 arm of a cutoff valve IA in the compressed air supply conduit I¹⁰. The conduit I¹⁰ is shown as also provided with an automatic pressure regulating valve J at the inlet sides of the valve I and IA. The pressure supply 15 pipe I¹⁰ is connected at the outlet sides of the valves to the compressed air inlet B² of the receptacle B by a flexible pipe section I¹¹, which permits the necessary movement of the receptacle B by the cylinder F, without requiring any movement of the compressed air supply pipe I¹⁰. It will be understood, of course, that the conductors 1, 2, 3 and 4 should include flexible portions for the same purpose.

25 In operation, after the apparatus is brought into condition for charging the mold A, with the latter in rotation, and with the receptacle B containing a sufficient amount of molten metal, and having its discharge nozzle C properly entered in the end of the mold, the previously closed valves I and IA, one at least of which was previously closed, are then both opened. In this initial charging condition of the apparatus 30 both scale beams D⁵ and D⁶ are up and the electromagnets H and HA are deenergized. As soon as the valves IA and I are opened compressed air passing through the conduit I¹⁰ quickly builds up the pressure in the top 35 of the receptacle B to a maximum fixed by the pressure regulating valve J. The pressure thus obtained in the top of the receptacle B forces molten metal out of the receptacle B through the outlet passage B' and nozzle C. The velocity of the issuing 40 jet will be the function of the pressure in the upper portion of the receptacle B, and should be sufficient to cause the jet to carry to the rear end of the mold where it impacts against the disk A² carried by the 45 end member A' of the mold. After a small portion of the amount of metal necessary to charge the mold has been expelled from the receptacle B, the decreased weight of the 50 latter permits the scale beam D⁵ to drop into engagement with the contact G, and thus energize the electromagnet H, whereupon the throttling valve I begins to close. As the throttling valve I closes, the pressure 55 maintained in the upper end of the receptacle B decreases, producing a corresponding reduction in the velocity of the jet stream, so that the latter drops short of the far end of the mold, and as the pressure in 60 the receptacle B continues to decrease, as

the valve I continues to close, the jet stream becomes shorter and shorter until finally it just clears the nozzle C. When the mold is thus completely charged, the decrease in weight of the receptacle B permits the scale beam D⁶ to engage the contact GA and energize the magnet HA, whereupon the cutoff valve IA is immediately closed. By proceeding in this manner the molten metal may be fed into the mold progressively along the length of the latter with the desired uniformity, and the mold may be completely charged within the very short period of time required for the production of a homogeneous casting.

80 The rate at which the valve I closes when the magnet H is energized may be varied, of course, by adjusting the bypass valve H⁵. Any fall in liquid metal level in the receptacle B as the mold charging operation 85 proceeds tends of itself to decrease the velocity of the jet stream, but this tendency is not substantial unless the horizontal cross section of the receptacle is small enough so that a very considerable decrease in weight 90 of the molten metal level occurs in charging a single mold. It will be understood, of course, that after the receptacle B has received its charge of molten metal and the cap B³ is put in place the weights on the scale beams D⁵ and D⁶ are adjusted to insure the successive depression of those beams after the proper weights of molten metal are discharged from the receptacle B. The receptacle B may, of course, be made large 95 enough to hold metal for charging a considerable number of molds one after another, and in this case the loading effect of weights on the beams D⁵ and D⁶ must be reduced after each mold charging operation. As 100 previously indicated, when the nozzle CC, shown in Fig. 3, is used with a sand lined mold AA, the cylinder F may be manipulated to slowly withdraw the nozzle CC from the mold during all or the final portion of the pouring operation.

110 In Fig. 6 I have illustrated a very simple form of mechanism for use in obtaining an automatically graduated jet stream velocity of the molten metal charged into the mold AA, shown in that figure. The mold charging apparatus shown in Fig. 6, comprises standpipe BB, having a curved portion B¹⁰ at the bottom which terminates in a horizontal nozzle adapted to project into the 115 end of the mold. The standpipe BB, as shown, is mounted on a carriage L movable toward and away from the mold on suitable track rails by means of the cylinder F, having its plunger F' connected to the carriage L. With the apparatus shown in Fig. 6 the velocity of discharge is determined by the head of the molten metal column in the conduit BB. The molten metal is poured from a suitable ladle, not shown, into the top of 120

125 130

the column BB rapidly enough so that the column will fill to its upper end before more than a small portion of the molten metal has had time to be discharged into the mold 5 through the restricted nozzle orifice. With this arrangement a small portion of the charge is supplied to the mold progressively along its length from its end adjacent the column BB to the opposite end as the head 10 in the column BB builds up, and then, as the head of molten metal in the column BB decreases, the mold is charged progressively from its remote end to its charging end. The nozzle B¹⁰ may be made longer and 15 slowly withdrawn from the mold during all or the final portion of the pouring operation. In the modification of the apparatus of Fig. 6, shown in Fig. 7, the body portion of the column BC is separated from the 20 curved nozzle portion B¹⁰ by a valve controlled port B¹¹. Flow through the port B¹¹ is controlled by a stopper like valve M, which extends up through the column BC, and has a down-turned portion outside of 25 the column connected to an operating lever M'. The latter is pivotally connected to the standpipe BC. With this apparatus the proper charge of molten metal may be put into the standpipe BC while the port B¹¹ 30 is closed by the valve M; when the latter is opened wide, the molten metal is discharged with an initial velocity high enough to carry it to the remote end of the mold. As the head of molten metal in the column 35 BC decreases, the jet velocity decreases, and the desired progressive discharge along the length of the mold is thus obtained. It will be understood, of course, that the horizontal cross section of the standpipe column BB or 40 BC may be varied along the length of the column to obtain any desired relation between the changes in jet velocity produced by the discharge of successive equal portions of molten metal, or nozzle B¹⁰ may be made 45 longer as shown in dotted lines and indicated at b¹⁰ in Figs. 6 and 7, and slowly withdrawn from the mold during all or the final portion of the pouring operation.

In the modified form of apparatus shown 50 in Figs. 8 and 9, a receptacle BD is employed, which is pivotally connected to its supporting carriage L, so that the receptacle may be swung from the horizontal position shown in full lines in Fig. 8 into the nearly 55 vertical position shown in dotted lines in that figure. As shown, the nozzle portion B¹⁵ of the receptacle BD, which extends at right angles to the length of the body portion of the receptacle, is journaled in the 60 bearing L² provided in the carriage L. A second coaxial trunnion like extension B¹⁶ of the receptacle BD coaxial with the nozzle B¹⁵ is journaled in a second bearing L³ provided on the carriage L. A cable L⁶, connected to the receptacle BD, at one end, and

to the elevated portion L⁰ of the carriage L, at its other end, runs over a pulley L⁵ journaled on the platform L⁴, and under a pulley L⁷, carried at the upper end of the plunger or piston rod of a vertical fluid pressure 70 motor cylinder L⁸ mounted on the carriage L. The molten metal for charging a mold AB, is put into the receptacle BD when the latter is in the position shown in full lines in Fig. 8. The upper surface level of the 75 molten metal in the horizontally disposed receptacle BD when filled, is below the discharge passage B¹⁷ through the nozzle portion B¹⁵. When motive fluid is supplied to the cylinder L⁸ and the pulley L⁷ is drawn down, the receptacle BD is turned from the full line position into the dotted line position of Fig. 8. This causes the molten metal content of the receptacle BD to be discharged 80 through the nozzle B¹⁵ with a jet velocity 85 at any instant which will depend upon the height of liquid level in the body of the receptacle BD above the discharge orifice B¹⁷ at the instant. By suitably regulating the speed with which the piston in the motor 90 cylinder L⁸ is moved downward, any desired progressive feed of molten metal along the length of the mold may be secured, or, as before noted, the nozzle B¹⁵ may be made longer as indicated at b¹⁵ in dotted lines in 95 Fig. 9 and slowly withdrawn from the mold during all or the final portion of the pouring operation.

The apparatus shown somewhat diagrammatically in Fig. 10, for charging the sand 100 lined mold AA, comprises a conduit O, shown as a trough having an open end. At the beginning of the mold charging operation proper, a portion of the conduit O, which is longer than the mold, is axially 105 disposed in the mold extending from the charging end to the opposite end of the mold, where the open end of the conduit abuts against, and is temporarily closed by a stop plate or valve member Q carried by a stem Q' splined in a sleeve carried by a bracket Q³ and in threaded engagement with a nut Q² swiveled in the bracket sleeve and provided with an operating hand wheel. The bracket Q³ is pivoted to a support Q⁴, 110 so that when the stem Q' and plate Q is withdrawn from the mold, as it may be by the rotation of the nut Q², the plunger Q' may be swung out of alignment with the mold if desired. The portion of the conduit O projecting out of the charging end of the mold in the condition of the apparatus shown in Fig. 10, extends under a ladle 115 spout P, through which the conduit O is supplied with molten metal. The projecting outer end of the conduit O is mounted on a carriage LA sliding along a guideway L²⁰ parallel to the length of the mold AA. The carriage LA is connected to the plunger 120 or piston rod of a fluid pressure motor cylin- 125

der F. By suitably manipulating the valve F² controlling the admission of the motive fluid to the motor cylinder F the conduit O may be withdrawn from the mold AA at 5 any desired rate.

With the apparatus shown in Fig. 10 the desired progressive charging of the mold AA, along the length of the latter, is obtained by manipulating the valve F² to 10 withdraw the conduit A from the mold at the proper velocity. As the conduit O is drawn out of the mold, the molten metal begins to discharge as soon as the end of the conduit is opened by its movement away 15 from the plate Q. The manner in which the molten metal is distributed along the length of the mold will obviously depend upon the rate at which the conduit O is withdrawn from the mold. In Fig. 11 I 20 have illustrated apparatus in which the stop plate QA, corresponding in function to the plate Q previously described, is journaled in the end member A²⁰ closing the bell end of the mold AA.

In Fig. 12 I have illustrated a modification of apparatus of the general type shown in Fig. 10 in which the portion of the conduit OA, projecting out of the mold at the beginning of the mold charging operation, 30 is of considerable length and in which this conduit is intended to be empty at the beginning of the mold charging operation. The proper quantity of molten metal for charging the mold AA in Fig. 12 is supplied 35 to the conduit OA through the ladle PA continuously during the mold charging operation in the course of which the conduit O is gradually withdrawn from the mold. To move the conduit OA into and out of 40 the mold I have provided in Fig. 12 a rack gear at the under side of the outer portion of the conduit, which is engaged by a spur gear R journaled on a supporting bracket R' and rotated by any suitable means which 45 I have not thought it necessary to illustrate. Adjacent the mold the conduit OA is supported on a roller R² journaled on a bracket R³.

In Fig. 13 I have illustrated apparatus 50 possessing some of the characteristics of the apparatus shown in Fig. 10, and some of the characteristics of the apparatus shown in Fig. 1. In the apparatus shown in Fig. 13 the conduit OB employed is substantially 55 identical with the conduit O of Fig. 10, but in this case, as in Fig. 12, the discharge end of the conduit OB is always open. The conduit OB is carried by the platform of a scale DA having wheels D' running along track 60 rails E as in Fig. 1. The scale DA is connected to the piston rod or plunger of a motor pressure cylinder FA. Also mounted on the platform of the scale DA is a molten metal receptacle BB, having a bottom discharge port B²⁰ which may be closed by a 65

valve member MA connected to an operating lever M¹⁰. The latter is connected to, and operated by the armature of an electromagnet S in such fashion as to automatically close the port B²⁰ when the scale lever D⁶ is 70 depressed and engages the contact G⁹ forming a part of the energizing circuit of the electromagnet S. The valve F' controlling the operation of the motor cylinder FA is automatically operated by an electromagnet 75 SA, which is energized when the scale beam D⁶ engages the contact G¹⁰ forming a part of the energizing circuit of the electromagnet SA. The rate at which the conduit OB is withdrawn from the mold when the valve 80 F' is turned to produce such withdrawal, is regulated by an adjustable throttling valve F³ in the motive fluid exhaust conduit F⁴.

The apparatus of Fig. 13 is shown in condition for starting the mold charging operation whenever the lever M¹⁰ is manually actuated to open the port B²⁰. When the port B²⁰ opens molten metal begins to pass from the receptacle BB into the conduit OB. On the 90 diminution in the weight of molten metal held in the receptacle BB occurring during the interval required for the molten metal to flow from the receptacle BB into the conduit OB, and out of the latter, is an amount 95 sufficient to supply all or a portion of the metal required in the bell portion of the pipe being cast, the scale beam D⁶ is depressed. This energizes the electromagnet SA and shifts the valve F' to cause the 100 withdrawal of the conduit OB from the mold. The metal continues to discharge from the receptacle BB into the trough OB as the latter is withdrawn from the mold, until the decrease in weight of the molten 105 metal in the receptacle BB permits the scale beam D⁶ to engage the contact G⁹. This energizes the electromagnet S and closes the port B²⁰.

While in accordance with the provisions 110 of the statutes I have illustrated and described the best forms of apparatus for, and the best modes of practising the invention now known to me, it will be apparent to those skilled in the art that changes in the 115 apparatus and methods illustrated and described may be made without departing from the spirit of my invention as set forth in the appended claims, and that in some cases some features of my invention may be 120 used to advantage without a corresponding use of other features of the invention.

Having now described my invention, what I claim as new and desire to secure by Letters Patent, is:

1. The method of making a tubular metal casting in an elongated mold rotating about a horizontal axis, which consists in supplying the molten casting metal to the mold in a jet and progressively varying the jet veloc- 130

ity to distribute the metal along the length of the mold.

2. In a centrifugal casting machine, the combination with a mold rotating about a horizontal axis, of mold charging means comprising a nozzle through which the molten metal is discharged into the mold and means for varying the pressure by which the molten metal is forced through said nozzle.

3. In a centrifugal casting machine, the combination with a mold rotating about a horizontal axis, of mold charging means comprising a molten metal containing receptacle having a nozzle outlet adapted to discharge a stream of molten metal into said mold and means automatically responsive to the change in weight of the metal in said receptacle occurring as the charging opera-

tion proceeds for causing the molten metal stream to impinge against the wall of the mold cavity progressively along the length of the mold.

4. In a centrifugal casting machine, the combination with a mold rotating about a horizontal axis, a molten liquid receptacle having a nozzle outlet at its bottom adapted to discharge a stream of molten metal into the mold, said receptacle being so vertically elongated and horizontally restricted that the change in head of molten metal occurring in a single mold charging operation will cause the jet to impinge against the wall of the mold cavity progressively along the length of the mold during the mold charging operation.

JAMES B. LADD.
